UNITED STATES PATENT OFFICE

153,262

DESIGN FOR A CHILD'S SLEEPING GARMENT

Earl E. Carpenter and Ellen Plucar, Superior, Wis.

Application October 10, 1946, Serial No. 133,868

Term of patent 14 years

(Cl. D92—2)

To all whom it may concern:

Be it known that we, Ellen Plucar and Earl E. Carpenter, citizens of the United States, residing at Superior, in the county of Douglas and State of Wisconsin, have invented a new, original, and ornamental Design for a Child's Sleeping Garment, of which the following is a specification, reference being had to the accompanying drawing, forming part thereof.

Fig. 1 is a front elevational view of a child's sleeping garment, showing our new design, and

Fig. 2 is a rear elevational view of the upper portion of Fig. 1.

The back of the garment is the same as the front thereof, except for the opening in the front.

We claim:

The ornamental design for a child's sleeping garment, substantially as shown and described.

EARL E. CARPENTER.
ELLEN PLUCAR.
